UNITED STATES PATENT OFFICE.

ZALMON G. SHOLES, OF WILMINGTON, DELAWARE, ASSIGNOR, BY MESNE ASSIGNMENTS, TO SHOLES STANDARD TYPEWRITER COMPANY, OF WILMINGTON, DELAWARE, A CORPORATION OF DELAWARE.

RIBBON-SHIFT FOR TYPE-WRITERS.

1,165,546.

Specification of Letters Patent. Patented Dec. 28, 1915.

Application filed December 15, 1914. Serial No. 877,849.

To all whom it may concern:

Be it known that I, ZALMON G. SHOLES, a citizen of the United States, residing at Wilmington, in the State of Delaware, have 5 invented certain new and useful Improvements in Ribbon-Shifts for Type-Writers; and I do hereby declare the following to be a full, clear, and exact description of the invention, such as will enable others skilled 10 in the art to which it appertains to make and use the same.

My present invention relates to an improved form of automatic ribbon feed for typewriters whereby the reversal of the ribbon is accomplished by simple and reliable 15 automatic means of novel construction, each time that either bobbin carrying the ribbon is emptied.

My improvement is applicable to a variety of types of machines and therefore 20 in my drawings I have omitted such parts of the machine as were not essential to cooperation with the working parts of my invention. These are shown in a preferred 25 form in front elevation in Figure 1, while Fig. 2 shows the same in elevation as seen from the right hand side of the machine, and Fig. 3 is a plan view of one of the ribbon-carrying bobbins with portion of the 30 top flange broken away.

The ribbon 10 is carried in a well known manner upon two bobbins 11 and 12 on opposite sides of the machine. The bobbin 11 is removably mounted in a well known manner 35 upon the revoluble shaft 13, and the bobbin is similarly mounted upon the shaft 14. Fast on the lower ends of these shafts are provided beveled gears 15 and 16, and one or the other bobbin is wound up through 40 its said gear wheel, by appropriate means. As is usual in these machines, the bobbin which is not being wound up is unwound by the tension exerted upon the ribbon by the other bobbin.

45 The preferred winding mechanism, which is shiftable so as to affect one bobbin at a time, and one after the other in alternation automatically, comprises a transverse driving shaft 17, impelled by a beveled gear 18, 50 which is in turn driven by the gear 19 moving intermittently with the carriage driving wheel 20, in a well known manner. This wheel acts on the carriage through a belt or strap 21 whose free extremity is fixed to

the carriage at 22. The gear 18 is fixed to 55 a sleeve 23 which is loose on the shaft 17, and is prevented from longitudinal movement (right or left of the machine) by a circular flange 24 whose edge turns in a recess in the abutment 25, fixed to any convenient portion 26 of the frame of the machine.

At one end of the sleeve 23 is an arm 27 carrying a pin 28. A sleeve 29 is fixed to the shaft 17, and carries an extension or extensions 30, engaging the pin 28 so as to slide freely along the same when the shaft 17 is moved longitudinally. By these means the rotary movement of the gear wheel 18 is always imparted to the shaft 17, whatever its position.

Each bevel gear 15 and 16 is driven by its own subordinate countershaft 31, 32, through bevel pinions 33, 34, meshing with 15 and 16. The rear ends of shafts 31, 32 75 are furnished with bevel gears 35, 36.

The main driving shaft 17 is furnished with pinions 37, 38, adapted to mesh (one at a time) with the gears 35 and 36, respectively. The shaft 17, and therefore the 80 bobbins, may be turned by means of the handle 39, if desired.

In order to lock the shaft 17 in one or the other extreme position automatically, I prefer to employ catches 40 and 41, pivoted to 85 the bearings 42, 43, and provided with extensions 44, 45. These catches are so proportioned as to drop by gravity into grooves 46 in the shaft 17, one of which is hidden in Fig. 1 by the bearing 42. Only one 90 groove is engaged by its locking catch at a time.

In order to provide means for automatic shifting of the shaft 17 at the proper time, so as to change the direction of movement 95 of the ribbon, I furnish said shaft with two short worms, 47 and 48, which are normally idle; and with these are associated corresponding movable abutments acting automatically one at a time to move the 100 shaft by furnishing a point of resistance for effective operative contact with the threads of said worms respectively. These automatic movable abutments may be of various forms, and may be variously operated without departing from this invention. For this purpose, however, I prefer the 105 structure illustrated, which may be de-

scribed as follows, with respect to the bobbin 12 (Fig. 2) only; it being understood that another structure of the same kind is associated with the bobbin 11, as shown at 5 the left in Fig. 1. Directly above the gear 16, there is pivoted at 49 a light flat lever having an upstanding short arm 50 and a long, substantially horizontal arm 51. The rear (vertically flattened) end of this longer 10 arm moves in a guide 52, and has a point 53, which is adapted to fall into the thread of the worm 48 when the arm 51 is depressed, thereby affording the movable abutment above referred to. At the same time 15 that the point 53 moves downward to engage the worm 48, a pin 54, also on the rear end of the arm 51, strikes the extension 45, and causes the corresponding catch to leave the groove 46, thus unlocking the shaft 17 20 and permitting the revolving worm 48 and its abutment 53 to coöperate in moving the shaft 17, so as to disengage the pinion 37, while bringing the opposite pinion 38 into effective mesh with the gear 36. Of course 25 the similar movable abutment with its pin, when its turn comes, will shift the shaft back again to the position shown in Fig. 1.

In order to accomplish the movement up and down of each abutment point 53 at the 30 proper time automatically, each bobbin has a central hollow cylindrical shell 55, suitably cut away to form a window 56 on one side (see Fig. 3). This cylinder 55 is open on the under side, where the end of the short 35 arm 50 enters the cylinder. A roller 57 is preferably provided at the end of the arm 50, and is so arranged that, when there is any ribbon wound on the bobbin shell, the weight of the long arm 51 keeps this roller 40 lightly pressed, against the ribbon and against the inner surface of the cylindrical shell 55, successively, as the bobbin turns. On the other hand, when the ribbon is so far 45 unwound as to uncover the window 56, the roller is allowed to move slightly outward through the window, and this movement is sufficient to cause the abutment point 53 to engage its worm, thus shifting the driving shaft 17, as above described, and causing the 50 now empty bobbin to reverse its movement and begin to wind the ribbon upon itself again, thereby pressing inward the roller 57, and arm 50, and lifting the point 53 away from its worm. After each shift of the 55 shaft 17, it is automatically locked at one

end or the other by the appropriate catch 40 or 41.

Various changes may be made in the arrangement and structure of this apparatus, without departing from the invention, and I do not limit myself to the details herein shown and described.

What I claim is—

1. In a typewriter, bobbins therefor, a shiftable driving shaft for said bobbins, a worm thereon, a movable abutment adapted to coöperate with said worm, a lock for said shaft and means for automatically releasing said lock while bringing said abutment into contact with said worm to shift said driving shaft, substantially as described. 70

2. In a typewriter, a bobbin upon which the ribbon is wound, a shiftable driving shaft for said bobbin, a tilttable catch for locking said shaft, and a pivoted lever having one arm adapted when moved to tilt said catch and a second arm normally making contact with said ribbon while on said bobbin, substantially as described. 75

3. In ribbon shifting means for typewriters, a transverse driving shaft having a worm near each end and provided with locking grooves, a tilting catch near each worm for engaging said grooves, a movable abutment for each worm adapted to move into 80 and out of engagement each with its appropriate worm and simultaneously to release the corresponding catch from its groove in the shaft, and means controlled by the ribbon movement for actuating said abutments 90 one at a time, substantially as described.

4. In ribbon shifting means for typewriters, a transverse driving shaft at the rear of the machine, ribbon bobbins near the front thereof, a worm near each end of said 95 shaft, and a two armed lever near each end of the machine, each lever being pivoted to tilt in a plane at right angles to said shaft and having one arm adapted to engage the ribbon and the other and longer arm adapted at its end to engage temporarily with its corresponding worm on said shaft, substantially as described. 100

In testimony whereof, I affix my signature, in presence of two witnesses.

ZALMON G. SHOLES.
